TIRE CHANGING STAND

James Kenneth Listebarger, Fairfax, Iowa

Application February 23, 1933. Serial No. 658,263

6 Claims. (Cl. 144—288)

The object of this invention is to provide a stand for carrying a wheel and tire, either in a substantially horizontal position, or in an approximately vertical position, whilst the tire is being changed, the device being equally useful, regardless of whether the rim is of the drop center type, or of the straight side type.

Another object of the invention is to provide a device of the class described, which may be placed close to a wall and can be operated to shift the position of the work table, without rendering it necessary for the operator to pull out the stand, away from the wall, the stand always keeping a fixed position with respect to the wall.

A further object of the invention is to provide a device of the class described, which, although adjustable to vary the position of the work table, will, nevertheless, maintain the work table rigidly in position, whether the work table be in an approximately horizontal position, or in an approximately vertical position.

Another object of the invention is to supply novel means for adjusting the position of the work table, taking up looseness of parts, and maintaining the work table rigid, when the work table is in an approximately vertical position.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in side elevation, a device constructed in accordance with the invention, the parts being in the positions that they will assume when the work table is held rigidly in an approximately horizontal position;

Fig. 2 is a top plan of the device arranged as shown in Fig. 1;

Fig. 3 is a side elevation, wherein the work table has been shifted to an approximately vertical position;

Fig. 4 is a front elevation, wherein the parts are in the position of Fig. 1;

Fig. 5 is an elevation showing a modification, parts being broken away.

In carrying out the invention, there is provided a frame F, which may be constructed variously. The frame F may embody a base 1, to which a vertical standard 2, of any desired construction, is secured. The standard 2 has a flattened upper end 3, carrying a pivot element 4, on which are mounted the inner ends of supports 5, disposed on opposite sides of the flattened end 3. The outer end of the supports 5 carries a pivot member 6, on which a bell crank lever 7 is fulcrumed, the bell crank lever extending between the supports 5. The bell crank lever embodies an inner or short arm 8, and an outer or long arm 9. The inner arm 8 of the bell crank lever has a thinned lower end 10.

There is a hub 11 on the bell crank lever 7, at the angle formed by the arms 8 and 9 of the bell crank lever. This hub 11 has a projecting spindle 12, on which a clamping nut 14 is threaded. The nut 14 holds a work table 15 on the spindle 12 in abutment with the upper end of the hub 11, the table 15 being provided with openings 30, arranged as desired, and adapted to receive the bolts or other securing elements (not shown) whereby the wheel (not shown) is secured to the work table. The particular arrangement of the openings 30 is a matter of choice, and the manufacturer can arrange the openings as he wishes. The hub 11 has another function, in that its lower end engages the upper edge of the supports 5, to keep the outer arm 9 of the bell crank lever in substantial alignment with the supports, when the parts are arranged as shown in Fig. 1.

In the outer end of the arm 9 of the bell crank lever 7 there is a pivot element 16, which is of considerable length, so as to project laterally, as shown in Fig. 4. The pivot element 16 carries the upper ends of downwardly extended props 17. The lower end of the props 17 is curved, and is spread apart slightly, so that the lower ends of the props 17 may span the standard 2, and be connected thereto by a pivot member 19.

The operating member for the stand is designated by the numeral 20, and is a lever of the first order, fulcrumed intermediate its ends at 21 on the intermediate portion of the props 17. The inner end portion of the operating lever 20 is designated by the numeral 22, and is pivoted at 23 to the lower ends of links 24, which extend upwardly on opposite sides of the flattened end 10 of the short arm 8 of the bell crank 110

lever 7, the parts 24 and 10 being pivotally connected, as indicated at 25.

There are laterally extended lugs 26 on the support 5, and into these lugs are threaded adjustable stops or abutments, such as screws 27. The long or outer arm 9 of the bell crank lever 7, the pivot member 16, and the props 17, constitute connected elements, and with one of these connected elements, for instance the pivot member 16, the screws 27 are adapted to engage.

If the wheel is of the straight-side type, it is bolted to the work table 15 with the table in the horizontal position of Fig. 1, but if the wheel is of the drop-center type, the work table is disposed in the position of Fig. 3, the position of the table being changed by pressing down on the outer end of the operating lever 20. It may be noted that at no time do any of the parts project to the right of the standard 2 in Figs. 1 and 2. Consequently, the device can be placed as closely as desired to the wall 31 and need not be moved with respect to the wall when the parts are shifted to and from the positions of Figs. 1 and 2.

When the device is arranged as shown in Fig. 1, the hub 11 on the bell crank lever 7 rests on the members 5. So far as any downward movement of the work table 15 is concerned, the parts 5 and 9 form one rigid side of a triangle, the other two sides of which are represented by the prop 17 and the standard 2, and the work table is rigidly supported in the position of Fig. 1.

When the parts are arranged as shown in Fig. 3, the work table 15 is supported in a predetermined position, because the pivot points 21, 23 and 25 are in a straight line, the inner end 22 of the operating lever 20 and the links 24 forming a rigid brace. Some times the parts 22 and 24 may form an obtuse angle, the pivot 23 moving a little to the left of the position shown, and the links 24 abutting against the lower end of the arm 9 of the bell crank lever 7.

In the absence of the screws or stops 27 the table 15 is held in the predetermined position of Fig. 3, in the sense that until the lever 20 is moved by an operator, the table will not tend to drop down to the position of Fig. 1, but will remain in the position of Fig. 3 while the work is being done on the tire or wheel. Theoretically, the work table 15 is rigid, as well as held in a predetermined position, but in practice the work table is not always rigid, because there will generally be a little play at some or all of the pivots 16, 6, 25, 4, 23, 21, 19, due to wear or to the inaccuracies always found in a machine not constructed with extreme precision. This play is not great enough to let down the table 15 from the position of Fig. 3 to the position of Fig. 1, but it may detract from the absolute rigidity of the table 15, and prove disconcerting or inconvenient to the workman. The play above referred to can be taken out of the machine by adjusting the stop screws 27 until they bear on the pivot member 16, when the parts are arranged as shown in Fig. 3.

In Fig. 5, parts hereinbefore described have been designated by numerals previously used, with the suffix "a". The table 15a has an upwardly extended hollow hub 50, which surrounds the nut 14a, with plenty of room for the nut to be turned. A threaded standard is shown at 51, and has an enlarged base 52 which is threaded into the hub 50. A wing nut 53 is threaded

on the standard 51 and cooperates with a washer 54 in holding the rim which is being worked upon, in place on the standard 51. If the operator wishes, he can detach the standard 51 by threading its base 52 out of the hub 50, and the article being worked upon then may be secured to the work table through the holes 30 of Fig. 2, it being recalled that these holes may be placed wherever desired.

Having thus described the invention, what is claimed is:

1. A stand of the class described, comprising a frame, a support pivoted at its inner end to the frame, a first lever fulcrumed on the outer end of the support and comprising inner and outer arms, a prop having its upper end pivoted to the outer arm of the first lever and having its lower end pivoted to the frame below the support, an operating lever fulcrumed intermediate its ends on the intermediate portion of the prop, a link pivoted at its lower end to the inner end of the operating lever, the upper end of the link being pivoted to the inner arm of the first lever, stop means carried by the first lever and engaging the support to maintain the support and the outer arm of the first lever substantially in longitudinal alinement when the support is in outstanding relation to the frame, and a work table carried by the first lever.

2. The stand of claim 1, and wherein the stop means is a hub on the first lever, and means on the hub for attaching the work table to the first lever.

3. A stand of the class described, comprising a frame, a support pivoted at its inner end to the frame, a first lever fulcrumed on the outer end of the support and comprising inner and outer arms, a prop having its lower end pivoted to the frame below the support, a pivot member connecting the upper end of the prop with the outer arm of the first lever, the prop, the pivot member and the outer arm of the first lever constituting connected elements, an operating lever fulcrumed intermediate its ends on the intermediate portion of the prop, a link pivoted at its lower end to the inner end of the operating lever, the upper end of the link being pivoted to the inner arm of the first lever, stop means carried by the first lever and engaging the support to maintain the support and the outer arm of the first lever substantially in longitudinal alinement when the support is in outstanding relation to the frame, a work table carried by the first lever, and a stop carried by the support and engaging one of said connected elements when the inner end of the operating lever and the link are in substantial longitudinal alinement.

4. The stand of claim 3, in combination with means for mounting the stop for adjustment to and from that one of said connected elements wherewith the stop engages.

5. The stand of claim 3, in combination with means for mounting the stop in such position on the support that the said pivot member is the one of said connected elements wherewith the stop engages.

6. The stand of claim 3, and wherein the stop is screw threaded for adjustment upon the support and so located thereon that the said pivot member is the one of said connected elements wherewith the stop engages.

JAMES KENNETH LISTEBARGER.
